UNITED STATES PATENT OFFICE.

JOHN E. SYKORA, OF WINDOM, MINNESOTA.

CARBURETING APPARATUS FOR INTERNAL-COMBUSTION ENGINES.

1,296,711.

Specification of Letters Patent. Patented Mar. 11, 1919.

Application filed February 16, 1917. Serial No. 149,009.

To all whom it may concern:

Be it known that I, JOHN E. SYKORA, a citizen of the United States, residing at Windom, in the county of Cottonwood and

5 State of Minnesota, have invented certain new and useful Improvements in Carbureting Apparatus for Internal-Combustion Engines; and I do hereby declare the following to be a full, clear, and exact description of 10 the invention, such as will enable others skilled in the art to which it appertains to make and use the same.

My invention has for its object to provide a carbureting apparatus for producing hydro-carbon vapor from a heavy hydro-carbon oil, such as kerosene, for use as a fuel 15 medium for internal combustion engines.

To the above end, the invention consists of the novel devices and combinations of devices hereinafter described and defined in 20 the claims.

The drawing, which is partly in section and partly in elevation, illustrates in a single view the invention incorporated in 25 the carbureter and the exhaust pipe of an internal combustion engine.

The numeral 1 indicates, diagrammatically and as an entirety, a carbureter, which may be of the standard or any desired make, 30 and the numeral 2 indicates a fuel intake pipe leading from said carbureter to an internal combustion engine, only the exhaust pipe 3 of which is shown. Gasolene, or other light hydro-carbon oil, is conveyed through 35 a pipe 4, from any suitable source of supply, such as a storage tank, to the carbureter 1. A valve casing 5 connects the pipe 4 to the carbureter 1, and has mounted therein, a three-way valve of well known construction.

40 The improved carbureting apparatus comprises a pipe 7, a container 8 for heavy hydro-carbon oil Z, hereinafter referred to as kerosene, and a jacket 9, all of which are concentrically arranged around the axis of the 45 exhaust pipe 3. The container 8, as shown, is in the form of a cylindrical shell, spaced apart from the pipe 7 and having an open top and a cast bottom with a flanged internally threaded axial opening into which the 50 receiving end of the pipe 7 is screwed. The improved apparatus is interposed in the ex-

haust pipe 3 and its pipes 7 form an intermediate section of said exhaust pipe. The delivery end of the receiving section of the exhaust pipe 3 is screwed into the cast bottom of the container 8.

The jacket 9 is of cylindrical form, with an open bottom and spaced apart from the container 8 to afford an air intake conduit 10, which completely surrounds said container. A cap 11 closes the upper end of the jacket 9 and is provided with a flanged axial opening into which the delivery ends of the pipe are screwed. The receiving end of the delivery section of the exhaust pipe 3 is 65 screwed into the flanged axial opening of the cap 11. This cap 11 is spaced above the container 8, to afford a mixing chamber 12.

A short fluid fuel supply pipe 13, extends 70 radially through the jacket 9 and connects the container 8, slightly above its bottom, with the valve casing 5. In one position of the three-way valve 6, the gasolene supply pipe 4 will be open to the carbureter 1, and the pipe 13 closed; and in another position 75 of said valve, the pipe 13 will be open to the carbureter, and the pipe 4 closed. A combined air and vapor pipe 14 connects the mixing chamber 12 with the carbureter 1.

The kerosene Z is fed under pressure, by 80 gravity or otherwise, through a supply pipe 15 leading from a suitable source of supply, such as a storage tank, not shown, to the container 8. Interposed in the kerosene supply pipe 15, close to the jacket 9, is a bowl 16, 85 having a port 17, into which the delivery end of the receiving section of the pipe 15 opens. Intermediately fulcrumed in the bowl 16 is a lever 18, having at its short end a needle valve 19 for closing the port 17. On the long 90 end of the lever 18 is a float 20, which normally holds the needle valve 19 in a position to close the port 17. Obviously, when the kerosene Z in the container 8 drops below a predetermined elevation, the float 12 will 95 open the needle valve 19 to admit a further supply of kerosene and then close the same when the kerosene in the container has again reached said predetermined elevation.

The operation of the improved carbureting apparatus may be briefly described as follows: In starting the engine, the valve 6

is set to close the pipe 13, and open the gasoline supply pipe 4. This valve 6 may be operated by any suitable connections, not shown, which preferably extend to the instrument board, or within easy reach of the driver. Under the suction stroke of the engine, a supply of gasoline is drawn into the carbureter 1 through the pipe 4, and a supply of air is drawn into said carbureter 10 through the air conduit 10, mixing chamber 12 and pipe 14. As the pipe 7 becomes heated, by the exhaust passing therethrough, the intake of air while passing through the conduit 10 is also heated, thereby greatly increasing 15 the efficiency of the fuel charge. The kerosene Z in the container 8 also becomes heated by its direct contact with the pipe 7, and the vapor rising therefrom commingles with the air in the mixing chamber 12, and is 20 drawn into the carbureter 1, through the pipe 14. After the kerosene Z has become sufficiently hot to vaporize, the valve 6 is operated to close the gasoline supply pipe 4 and open the pipe 13 to permit the kerosene 25 to be drawn, under the suction stroke of the engine, from the container 8 through the pipe 13, valve casing 5 and into the carbureter 1. With the valve 6 thus set, the engine continues to run on a fuel charge of 30 kerosene.

The above described invention, while extremely simple and easy to apply to carbureters of various different makes and to the exhaust pipe of an explosive engine, has in 35 actual usage proven highly efficient for the purpose had in view.

While the invention is shown in connection with a vertical exhaust pipe, it is, of course, understood that the same may be 40 used in connection with a horizontally disposed exhaust pipe or one that is set at an angle with respect thereto.

What I claim is:

1. The combination with the carbureter 45 and exhaust pipe of an internal combustion engine, of a heavy hydro-carbon oil container surrounding the exhaust pipe, a mixing chamber also surrounding the exhaust pipe and into which the container opens, an air supply conduit leading to the mixing chamber, a vapor conduit leading from the mixing chamber to the carbureter, a liquid fuel intake pipe leading from the container, a light hydro-carbon oil supply pipe, and 50 means for connecting either said intake pipe or supply pipe to the carbureter, at will.

2. The combination with the carbureter 55 and exhaust pipe of an internal combustion engine, of inner and outer jackets surrounding the exhaust pipe, said two jackets being closed at opposite ends, the closed end of the outer jacket being extended outward of the 60 open end of the inner jacket to afford a mixing chamber, said inner and outer jackets being spaced apart from each other and the latter from the exhaust pipe to afford there- 65 between a heavy hydro-carbon oil container

ing chamber, said inner and outer jackets being spaced apart from each other and the latter from the exhaust pipe to afford there- 70 between a hydro-carbon oil container and an air intake conduit, respectively, a vapor conduit leading from the mixing chamber to the carbureter, a liquid fuel intake pipe leading from the container to the carbureter, and a liquid fuel supply pipe leading to the container.

3. The combination with the carbureter and the exhaust pipe of an internal combustion engine, of a hydro-carbon oil container surrounding the exhaust pipe, a mixing chamber into which the container opens, an air supply conduit leading to the mixing chamber, an air and vapor conduit leading 80 from the mixing chamber to the carbureter, a liquid fuel intake pipe leading from the container to the carbureter, and a float controlled supply pipe leading to the container.

4. The combination with the carbureter 85 and the exhaust pipe of an internal combustion engine, of a hydro-carbon oil container surrounding the exhaust pipe, a mixing chamber into which the container opens, an air supply conduit leading to the mixing 90 chamber, an air and vapor conduit leading from the mixing chamber to the carbureter, a liquid fuel intake pipe leading from the container, a supply pipe, and a three-way valve connecting the liquid fuel intake pipe 95 and the supply pipe to the carbureter.

5. The combination with a carbureter and the exhaust pipe of an internal combustion engine, of a heavy-carbon oil container surrounding the exhaust pipe and having an open top, a supply pipe leading to the container, a float control in the supply pipe for keeping the oil in the container at a predetermined elevation, a jacket surrounding the container and spaced apart therefrom to afford an air intake conduit, said jacket having an open lower end, a cap closing the upper end of the jacket and spaced above the container to afford a mixing chamber, an air and vapor conduit leading from the mixing chamber to the carbureter, a liquid fuel supply pipe leading from the container, a light hydro-carbon oil supply pipe, and a three-way valve connecting the two last noted pipes to the carbureter.

6. The combination with the carbureter and exhaust pipe of an internal combustion engine, of inner and outer jackets surrounding the exhaust pipe, said two jackets being closed at opposite ends, the closed end of the outer jacket being extended outward of the open end of the inner jacket to afford a mixing chamber, said inner and outer jackets being spaced apart from each other and the latter from the exhaust pipe to afford there- 115 between a heavy hydro-carbon oil container

and an air intake conduit, respectively, a vapor conduit leading from the mixing chamber to the carbureter, a liquid fuel intake pipe leading from the container, a light hydro-carbon oil supply pipe, and means for connecting either said intake pipe or supply pipe to the carbureter, at will.

In testimony whereof I affix my signature in presence of two witnesses.

JOHN E. SYKORA.
